UNITED STATES PATENT OFFICE.

ALVIE R. MARTIN, OF STONEFORT, ILLINOIS, ASSIGNOR OF ONE-HALF TO J. V. TRAMMELL, OF STONEFORT, ILLINOIS.

RAIL-JOINT.

1,279,391.

Specification of Letters Patent. Patented Sept. 17, 1918.

Application filed November 24, 1917. Serial No. 203,821.

To all whom it may concern:

Be it known that I, ALVIE R. MARTIN, a citizen of the United States, residing at Stonefort, in the county of Williamson and 5 State of Illinois, have invented certain new and useful Improvements in Rail-Joints, of which the following is a specification.

This invention relates to an improved rail joint and has as its primary object to provide a construction wherein the coacting rail ends will be connected in such manner that one rail must be axially rotated eccentrically with respect to the other rail before the rail ends may become disengaged and thus providing an effective lock for the rail ends.

A further object of the invention is to provide a construction wherein one rail must be axially rotated in a direction upwardly and inwardly with respect to the other rail 10 in order to disengage the rail ends so that the weight of the first rail mentioned will normally act to hold the rail ends securely locked together and so that the weight of 15 rolling stock upon the rails will tend to bind the rail ends in locked engagement with each other.

A further object of the invention is to provide a combined chair and locking plate at the rail ends for preventing axial rotation of one rail with respect to the other and thus securely locking the rails together.

The invention has as a still further object to provide a lock between the rail ends of such nature that relative vertical movement 35 of the ends of the rails will be eliminated.

And the invention has as a still further object to provide an arrangement wherein the rails may, when desired, be easily and quickly disengaged.

40 Other and incidental objects will appear as the description proceeds and in the drawings wherein I have illustrated the preferred embodiment of the invention and wherein similar reference characters designate corresponding parts throughout the several views:

Figure 1 is a fragmentary perspective view showing successive rails formed with my improved joint and illustrating the manner in which the said rails are connected,

50 Fig. 2 is a horizontal sectional view showing the locking tongue of the joint in cross section,

Fig. 3 is a detail perspective view particularly illustrating the manner in which the

coacting ends of the rails are formed to provide the joint, this view illustrating the locking tongue and the socket of the joint in detail, and

Fig. 4 is a vertical sectional view particularly showing the manner in which the locking tongue of the joint is transversely curved.

Referring more particularly to the drawings, a railway rail is indicated at 10. A second rail is indicated at 11. Each of these 5 rails includes the usual base flange, web and tread. At its adjacent extremity, the web of the rail 10 is formed with a thickened portion 12 and projecting longitudinally from the adjacent end of the rail is a locking tongue 13. This locking tongue is, as particularly shown in Fig. 2, substantially T-shape in cross section and thus includes a web 14 and a head 15 providing flanges or shoulders 16 at opposite sides of the web. 70 The locking tongue 13 is transversely curved into arcuate form and, as particularly shown in Fig. 3, extends from the bottom of the base flange of the rail across the adjacent end thereof to one side of the enlarged portion 12 of the rail, the upper side of the said tongue being spaced below the tread of the rail. The locking tongue is thus disposed eccentrically with respect to the longitudinal axis of the rail and, of course, the bottom longitudinal edge of the said tongue is disposed flush with the bottom face of the base flange of the rail while the upper longitudinal edge of the said tongue is disposed flush with the face of the enlarged portion 80 12 of the rail, at the adjacent side thereof.

The web of the rail 11 is, at its adjacent extremity, provided with an enlarged portion 17 and formed in the said portion of the rail to open through the adjacent end 95 thereof is a socket 18 substantially T-shape in cross section to receive the locking tongue 13 of the rail 10. The socket 18 is thus formed at its inner extremity with a channel 19 to accommodate the head 15 of the 100 said tongue. Extending from this channel is a reduced throat 20 to accommodate the web 14 of the locking tongue and defining, at the junction of the throat with the channel, shoulders 21 to coact with the lateral shoulders 16 of the head 15 of the tongue. As particularly shown in Figs. 3 and 4, the socket 18 is of arcuate form or is transversely curved to conform to the curvature 105 of the locking tongue. At its lower longi- 110

- tudinal extremity, the said socket opens through the base flange of the rail while the upper longitudinal extremity of the said socket opens through the enlarged portion 5 17 of the rail at the adjacent side thereof and at a point below the tread of the rail. This socket is thus also disposed eccentrically with respect to the longitudinal axis of the rail.
- 10 Mounted to coöperate with the rails 10 and 11 at the coacting ends thereof is a combined chair and locking plate 22 which is arranged to extend transversely beneath the rail ends at the joint therebetween for rigidly supporting the ends of the rails upon a tie. Formed on the said plate to engage over opposite corresponding margins of the base flanges of the rails are locking flanges 23. The plate 22 may be secured in position for supporting the rail ends by ordinary railway spikes or in any other approved manner.
- As will now be readily understood upon reference to Fig. 3 of the drawings, the rail 10 is connected with the rail 11 by positioning the lower longitudinal edge of the locking tongue 13 in the outer longitudinal end of the socket 18 and then axially rotating the rail 10 eccentrically with respect to the rail 11 to ride the locking tongue into the said socket. In this connection, it will, of course, be understood that the end of the rail 10 opposite to that equipped with the tongue 13 is provided with one of the sockets 35 18 while the succeeding rail is formed at its adjacent end with one of the locking tongues. Accordingly, in Fig. 1, I have for convenience shown such succeeding rail at 24 and have indicated the parts of the joint between the said rail and the rail 10 by the same reference numerals employed in describing the connection between the rails 10 and 11. The rails may thus be easily and quickly connected and attention is now directed to the fact that, as will be understood upon an inspection of Fig. 4, the rail 10 will normally gravitate to ride the locking tongue 13 through the socket 18. Accordingly, the weight of the rail 10 will normally act to hold the rail ends locked together. After the rail 10 has been axially rotated, as previously indicated, to connect the rails, the plate 22 is moved into position beneath the rail ends when the flanges 23 of the said plate will engage with the flanges of the rail 10 to prevent retrograde axial rotation of the said rail and consequently lock the rails together. When so locked together, the head 15 of the locking tongue

is, as shown in detail in Fig. 2, loosely received within the channel 19 of the socket 18 while the web 14 of the said tongue freely fits through the throat 20 of the said socket so that the rail ends may move longitudinally with respect to each other to compensate for such expansion and contraction as may be caused by change in weather conditions. However, as will be clear, the shoulders 16 of the head 15 of the locking tongue will coact with the shoulders 21 of the socket to prevent longitudinal displacement of the rail ends.

From the preceding description, it will now be observed that the rail 10 must be axially rotated in a direction upwardly and inwardly eccentrically with respect to the rail 11 in order to disconnect the rails. The possibility of accidental disengagement of the rail ends is thus reduced to a minimum. Furthermore, it will be seen that the weight of rolling stock upon the rails will tend to bind the rail ends into more secure engagement with each other so that any tendency toward spreading of the rails will be materially counteracted, while vertical movement of one rail end with respect to the other will be practically eliminated.

It will therefore be seen that I provide a particularly simple and efficient construction for the purpose set forth and a joint which will form the rails into practically a solid unit. At the same time, the rails may, however, when desired, be easily disconnected.

Having thus described the invention, what is claimed as new is:

1. A rail joint including coacting rail ends one formed with an arcuate downwardly directed socket opening through one side of the said rail end, and an arcuate locking tongue projecting longitudinally from the other rail end for engagement in said socket.
2. A rail joint including coacting rail ends one formed with an arcuate socket opening through the bottom face and one side face of the said rail end, and an arcuate locking tongue projecting longitudinally from the other rail end and adapted to slidably engage in said socket.
3. A rail joint including coacting rail ends one formed with an arcuate socket substantially T-shape in cross section, and an arcuate locking tongue projecting longitudinally from the other rail end and substantially T-shape in cross section to engage within said socket.

In testimony whereof I affix my signature.

ALVIE R. MARTIN. [L. S.]
